UNITED STATES PATENT OFFICE.

ELIZABETH COCHRANE SEAMAN, OF NEW YORK, N. Y.

DESIGN FOR A STAND.

SPECIFICATION forming part of Design No. 35,394, dated December 3, 1901.

Application filed October 25, 1901; Serial No. 80,018. Term of patent 3½ years.

To all whom it may concern:

Be it known that I, ELIZABETH COCHRANE SEAMAN, a citizen of the United States, residing in the borough of Manhattan, city, county, and State of New York, have invented and produced a certain new, useful, and original Design for Stands, of which the following is a specification.

In the accompanying drawing I have shown a stand embodying my design.

In the drawing, *a* indicates the base of the stand of a general globular form. This base

is surmounted by a column *b*, terminating at the top in a shelf *c*. A short distance below the shelf *c* is a larger shelf or table *d*, having 15 upturned edges *e*.

What I claim is—

The design for a stand substantially as herein shown and described.

ELIZABETH COCHRANE SEAMAN.
